DESIGN FOR A SCOOTER

Joseph B. Eck, Sheboygan, Wis.

Application April 5, 1937, Serial No. 68,566

Term of patent 7 years

To all whom it may concern:

Be it known that I, Joseph B. Eck, a citizen of the United States, residing at Sheboygan, in the county of Sheboygan and State of Wisconsin, have invented a new, original, and ornamental Design for a Scooter, of which the following is a specification, reference being had to the accompanying drawing, forming part thereof.

In the drawing:

Fig. 1 is a front and side perspective view; Fig. 2 is a top plan view of the scooter; and Fig. 3 is a front view of the scooter, showing my new design.

I claim:

The ornamental design for a scooter, substantially as shown.

JOSEPH B. ECK.
